UNITED STATES PATENT OFFICE.

GEORGE H. MALOTT, OF LOS ANGELES, CALIFORNIA.

COLLAPSIBLE TRAVELER'S DESK.

Application filed July 20, 1925. Serial No. 44,872.

To all whom it may concern:

Be it known that I, GEORGE H. MALOTT, a citizen of the United States, and resident of Los Angeles, county of Los Angeles, State 5 of California, have invented new and useful Improvements in a Collapsible Traveler's Desk, of which the following is a specification.

This invention relates to collapsible furniture, and especially to a knock-down, portable writing table and desk.

An object of this invention is to provide a writing desk and table having detachable legs and a collapsible pigeonhole top for the 15 purpose of permitting the whole to be compactly arranged so as to be fitted in a thin carrying case or box of handy size.

Other objects and advantages will be made manifest in the following specification of an 20 embodiment of the invention here illustrated: it being understood that modifications, variations and adaptations may be resorted to within the spirit of the invention as it here claimed.

25 Figure 1 is a perspective of the set-up table and desk, its leafed drawer being extended.

Figure 2 is a perspective of the detached, top back.

30 Figure 3 is a perspective of the folded pigeonhole top back.

Figure 4 is a perspective of the folded pigeonhole bottom.

Figure 5 is a detail of the leg assembly.

35 Figure 6 is a section of a leg-post and its removed dowel.

Figure 7 is a section of the detached leg coupling.

40 Figure 8 is a perspective of one of the partitions.

The device comprises a table top 2 and its permanent frame which includes corner post stubs 3 and side and back strips 4, and a front drawer rail 5.

45 On the rail is a slideable drawer 6 having a top leaf 7 which is hinged at 8 to allow of its being opened when the drawer is pulled out to limit. The object and advantages of this is to increase the effective top area of the table and at the same time have a compartment in the desk for various purposes and for packing desk parts in the table drawer.

50 Each corner post has a dowel pin socket 10 to receive a long dowel pin 11 which is securable by a thumb-screw 12 when the pin

is inserted preparatory to setting up the table. Also, each leg-post 3 is reduced to form a lug 3^a to snugly fit into an attachable, square ferrule 13 having a clamp 60 screw 14.

A set of separate legs 15 is provided and each has a reduced top end 16 to snugly fit into its ferrule 13. Each leg 15 has a deep pin hole 17 for its half of a dowel pin 11, 65 and it has a thumb screw 18 for securing the pin when inserted.

The ferrule 13 is of a length equal to the total lengths of lugs 3^a—16 of a leg and leg post and the set-screw 14 is designed to 70 clamp onto both and hold them assembled.

A pigeonhole top structure includes a thin bottom having halves 20—20 transversely hinged at 21 to fold up and pass into drawer 6. When unfolded the bottom about equals 75 the length of the table top 2 and its upper face has cross-channels 22. Into these channels are adapted to stand a series of vertical partitions 25 suitably spaced and each having hinges 26 foldably attaching it to a top 80 or shelf 27, which is centrally divided and hinged at 28.

The endmost partitions 25 are grooved at 29 in the inner faces, and the central partition is grooved at 30 in both faces, and when 85 the partitions are set up as in Fig. 1, then a back having hinged parts 31 is slipped down in the grooves 29—30 at the rear ends of the partitions. Intermediate partitions 25^a do not extend beyond, but abut against the 90 back 31.

All of the parts are made of light material of suitable dimension to obtain strength.

It will be seen that the legs 15 and the ferrules 13 can be readily detached to dismantle the table, and that the pigeon-hole structure comprises a three-unit organization, namely the foldable bottom 20; the foldable top and partitions 27—25, and the foldable back 31, all of which, when extended are of a length greater than the drawer 6, and which may be folded separately and packed in the drawer, as, also, may be the ferrules.

The cover 7 of the drawer forms an extension top for the desk or table.

Wholly detached drawers 33 are provided for pigeonholes.

What is claimed is:

1. A collapsible pigeon-hole structure for 110 a traveller's desk, said structure being packable in a drawer of the desk which is of less

- length than the extended structure; said structure including a two-piece bottom having its sections hinged so as to be extended into alignment, a two-piece top, a series of 5 transverse partitions for spacing the top from the bottom, and a back having two hinged sections unfoldable into alignment, said back forming means to secure the bottom and the top in their extended positions.
- 10 2. A collapsible pigeon-hole structure comprising a bottom having hinged sections unfoldable into alignment, a top having hinged sections unfoldable into alignment, a back having hinged sections unfoldable into alignment, and a series of transverse
- 15

wall partitions for spacing the top and the bottom and interlockable with the set up back.

3. A collapsible pigeonhole structure comprising a bottom having hinged sections unfoldable into alignment, a top having hinged sections unfoldable into alignment, a back having hinged sections unfoldable into alignment, and a series of transverse 20 wall partitions for spacing the top and the bottom and interlockable with the set up back; the partitions being hinged to and across the top, and the bottom having channels for the partitions. 25

GEORGE H. MALOTT.
